UNITED STATES PATENT OFFICE.

OTTO KROGH, OF DETROIT, MICHIGAN.

INTERNAL-COMBUSTION ENGINE.

Application filed November 12, 1925. Serial No. 68,689.

This invention relates to internal combustion engines of the double acting type although the principle involved may be also employed in connection with other types of internal combustion engines.

An object of the invention resides in the provision of separate compression cylinders which may be positioned laterally with respect to the explosion cylinders, and in which the cylinder charges are compressed and then directed to the explosion chamber.

Another object of the invention consists in so arranging both the explosion cylinder and the compression cylinder that the respective pistons thereof may both be attached to the same piston pin which in turn has two connections with the main crank shaft.

A further object of the invention resides in a construction in which a much lighter flywheel may be employed and in which the flywheel may be positioned midway of the length of the crank shaft rather than at an extreme end thereof.

Another object of the invention is to so construct and combine the parts that the engine is one of extreme simplicity comprising few parts and susceptible of production at a relatively low cost.

Other objects and advantages of the invention will be apparent from the following description when taken in connection with the accompanying drawings in which:

Figure 1 is a vertical longitudinal section through one embodiment of the invention employing two explosion cylinders.

Figure 2 is a rear elevational view of the engine shown in Figure 1.

Figure 3 is an end elevational view showing the carburetor and connections in full lines.

Figure 4 is a fragmentary sectional view of one end of one of the compression cylinders.

Figure 5 is an elevational view taken at the side opposite to that shown in Figure 2.

Figure 6 is a vertical sectional view taken on the line 6-6 of Figure 5, and

Figure 7 is a fragmentary horizontal section through the upper portion of the casting.

Referring to the drawings more in detail the numeral 1 designates generally the crank case in which is mounted the crank shaft 2 provided with the number of crank arms 3 desired, and while four such arms are shown

in the present embodiment of the invention it will be apparent that this number may be increased or decreased depending upon the number of explosion cylinders required. 60

Mounted above the crank case are two double acting explosion cylinders 4 each provided with the usual water jackets 5. These cylinders 4 are formed with an explosion chamber 6 at each end thereof provided with a sparking device 7 (Fig. 2). Each cylinder 4 is also provided with a double piston 8 which is closed at its outer ends, and with charge receiving inlets 9 to be later described. 70

Positioned adjacent each explosion cylinder 4 but spaced therefrom is a compression cylinder 10 in which is mounted a double piston 11 having its outer ends open as shown in Figures 1 and 4. The extreme ends of the cylinders 10 are provided with outlets 12 which are connected by conduits 13 with the inlets 9 of the explosion chambers, and it should here be noted that these inlets are located at points remote from the ends of the cylinders 4; i. e., at substantially the inner limit of the stroke of the piston 8. 75

On the side of each compression cylinder 10 opposite to the outlet 12 is an intake valve 14 positioned in the intake manifold 15 to which may be attached any type of carburetor 16. 85

I will now describe the structure by which the pistons 8 and 11 are operated.

A piston pin 17 extends through the pistons 8 and 11 of each set of cylinders 4 and 10 and has connected thereto a connecting rod 18 as clearly depicted on Figure 1. This connecting rod is located between the two cylinders and has its opposite end attached to the crank arm 3. Piston pin 17 is also provided with an extension 19 to which is attached a connecting rod 20 having its opposed end associated with a crank arm 3. Obviously a clearance must be provided for the reciprocation of the piston pin 17 and for this purpose the cylinders 4 and 10 are provided with the vertically extending slots 21 and 22 respectively, these slots being closed by the side walls of the elongated pistons 8 and 11. 95

Exhaust ports 23 (Fig. 2) are formed in the walls of the cylinders 4 at points opposite the intake ports 9, and these ports communicate with exhaust pipes 24 leading to the atmosphere. Circulation of a cooling fluid is provided for in the usual manner by 110

the pipes 25 which, communicate with the water jacket 5, and which may be connected to the radiator by the usual hose couplings (not shown).

5. In the preferred form of the invention the flywheel 26 is mounted intermediate the ends of the crank shaft 2 and is geared to the light dynamo 27 (Fig. 3) and the starting motor 28. The entire engine if preferred may be enclosed within a casing 29.

10. From the foregoing description taken in connection with the accompanying drawings it will be apparent that I have devised a simple and novel construction by which the charges for internal combustion engines of any type may be compressed independently of the explosion cylinders, that the engine will generate considerable power even at low speeds, and will be almost vibrationless 15 in operation.

15. In accordance with the patent statutes I have described what I now believe to be the best embodiment of the invention, but I do not wish to be understood thereby as 20 limiting myself or the scope of the invention, as many changes and modifications may be made without departing from the spirit of the invention; all such I aim to include in the scope of the appended claims.

25. What I claim as new and desire to secure by Letters Patent is:

1. In combination an explosion cylinder and a compression cylinder arranged adjacent thereto and parallel therewith, pistons 30 arranged in each of said cylinders, a crank shaft, connecting rods between said crank shaft and pistons, and conduits leading from the extreme ends of the compression cylinder to the opposed ends of the explosion cylinder.

35. 2. In combination an explosion cylinder and a compression cylinder adjacent thereto and parallel therewith, pistons arranged in each of said cylinders, means for operating 40 said pistons in unison, conduits leading from the extreme ends of the compression cylinder

45. der to the opposed ends of the explosion cylinder, and an intake valve for each end of the compression cylinder.

50. 3. In a double acting explosive engine a cylinder having an explosion chamber at each end thereof, a double piston in said cylinder, a compression cylinder adjacent said first-named cylinder, a double piston in said compression cylinder, means for operating 55. said pistons in unison, and conduits leading from the outer extreme ends of the compression cylinder to the inner ends of the explosion chambers.

55. 4. In a double acting explosive engine a cylinder having an explosion chamber at each end thereof, a double piston in said cylinder having its outer ends closed, a compression cylinder adjacent said first-named cylinder, a double piston in said compression cylinder having its outer ends open, 60 means for operating said pistons in unison, and conduits leading from the outer extreme 65 ends of the compression cylinder to the inner ends of the explosion chambers. 70

65. 5. In a double acting explosive engine a cylinder having an explosive chamber at each end thereof, a compression cylinder spaced slightly from said first-named cylinder, double pistons in each of said cylinders, a piston pin extending through both of said double pistons, a crank shaft, and a connecting rod positioned between said cylinders and connected to said piston pin and 75 crank shaft. 80

75. 6. In combination an explosion cylinder and a compression cylinder spaced apart, a piston in each of said cylinders, a piston pin extending through both of said pistons and provided with an extension, a crank shaft, 85 connecting rods attached to said crank shaft, one of said connecting rods being positioned between said cylinders and connected to an intermediate portion of said piston pin, the other connecting rod being connected to the 90 extension of said piston pin.

OTTO KROGH.
